DOOR HANGER

Filed June 5, 1922

FIG. 1

Patented July 24, 1923.

1,462,694

UNITED STATES PATENT OFFICE.

FRANCIS K. FASSETT, OF DAYTON, OHIO.

DOOR HANGER.

Original application filed June 22, 1914, Serial No. 846,450. Divided and this application filed June 5, 1922. Serial No. 565,971.

To all whom it may concern:

Be it known that I, FRANCIS K. FASSETT, a citizen of the United States, residing at Dayton, in the county of Montgomery and 5 State of Ohio, have invented a new and useful Improvement in Door Hangers, of which the following is a specification.

My invention relates to door hangers of the type wherein rubbing contacts are, as 10 far as possible, replaced by rolling contacts, and one of the objects of the invention is to confine the rubbing contacts to points where very little pressure is sustained. Another object is to provide that such metallic parts 15 as have rubbing contact with non-metallic parts shall also have rolling contact with metallic parts, whereby they will receive a planishing effect in the normal operation of the hanger. Another object is to provide 20 simple and effective means for attaching the door to the hanger after the latter is in place, by which the door can also be raised or lowered, and plumbed. Another object is to construct the hanger in such manner that 25 the door may hang plumb without putting unequal strains on the hanger parts, even though the parts are not perfect, or are imperfectly installed. Another object is to construct a hanger in such a manner that 30 drawn steel can be used to a great extent, and castings nearly, if not wholly, eliminated.

The present application is a division of my application, Serial Number 846,450, filed 35 June 22, 1914.

In the accompanying drawing,

Figure 1 is an elevational view of my hanger, supporting a fragment of a door;

Figure 2 is a plan view of the hanger;

40 Figure 3 is a transverse sectional view taken on line 3-3 of Figure 1;

Figure 4 is an isometric view of the links whereby the wheels are connected and maintained at a fixed distance apart;

45 Figure 5 is an isometric view of the arrangement for connecting the hanger to a door, and

Figure 6 is an isometric view of a washer forming a part of the structure shown in 50 Figure 5.

Referring now to Figures 1, 2 and 3, a single track 50 is secured to the wall by any well known means, and grooved wheels 51, having axles 52, carry a rider composed of 55 parallel strips 53-53, one strip resting on the axles at each side of the wheels. The

strips are united by screws 54 passing through spreaders 55, and also by the upper ends of the pendants 56 which, being formed into a U shape are riveted to the strips. The 60 lower ends of the pendants are bent inwardly to form feet and are provided with open slots 57 to receive the bodies of bolts 58. A hole 59 is formed in each pendant of such size as to allow the head of the bolt to pass 65 through, these holes uniting with the slots 57, thereby enabling the door to be attached after the hanger is in place and the bolts screwed into or otherwise attached to the door. The holes extend a short distance on 70 the horizontal part of the pendants, as will be seen in Figure 5. A clip 60 having upturned flanges 62, and a slot which reaches from one flange to the other is strung on each bolt above the jamb nut 63, and after 75 the bolts are in place in the slots 57 the clips are pushed up into place, the flanges 62 serving to close the ends of slots 57. After the nuts 63 are screwed up against the clips, or even near them, it is impossible for the 80 bolts to slip out of the pendent slots. The threads of the bolts may be slightly mutilated after the nuts are screwed up, to prevent the nuts working far enough down to let the bolts out. 85

The wheels 51 are connected together by links 65, preferably made of wood and boiled in paraffine to furnish lubrication and at the same time render the wood insensible to atmospheric conditions. Recesses 67 (see Figure 4) are formed in the upper edges of the links by boring holes so close to the upper edge that the edge is cut out, forming narrow slots. When these links are hung on the axles of the wheels a 90 narrow portion of the top of the axle is left exposed, thus affording an opportunity for the rider bars 53 to rest on the axles. As the slots in the upper edges of the links are narrower than the diameter of the axles, 95 the axles are enabled to support the links. This is very clearly shown in Figure 1. In Figure 3 it will be seen that the links and the rider bars are in contact with the same zones of the axles. In other words, the 100 bars 53 are in the same vertical plane as the links 65. The links are connected together by spreaders 66 and screws which pass through the links and into the spreaders, thus preventing them from slipping off of 110 the ends of the axles.

In addition to economizing space, which

is an important consideration in a door hanger, putting the riders and links in the same zone on the axle has another important use: the axles are fixed in the hubs of the 5 wheels and there is a rolling action between the axles and the edges of the rider bars 53 similar to the rolling action which takes place between the treads of the wheels and the track 50. This rolling action has the 10 effect of planishing the axles, giving them a hard, glossy, rust-free surface, which rotates in the recesses 67 in the links with a very slight amount of friction. When it is recalled that the links are made of wood and 15 are therefore very light, and it is realized that the only friction between the axles and the wood is that which is due to the weight of the links, it will be realized how nearly frictionless this hanger is.

20 For the purpose of avoiding rubbing at points where metal contacts with metal, the parts are specially formed. The treads of the wheels are crowned and the flanges flare outward. As the tread of the track 50 is 25 flat, it follows that the points of contact between the flanges of the wheels and the corners of the track are just the same distance from the axis of the wheel as the portion of the wheel tread which contacts with the 30 track. Therefore the contact between the flanges and the track is a rolling instead of a rubbing contact. The same principle is applied at the hubs, through making the hubs of the wheels slightly conical. The 35 only part of the hubs that contacts with the rider bars is the part which is of the same diameter as the axle, and thus rubbing contact is avoided at this point. While it might be thought that the limitations imposed by considerations of economy in the 40 commercial application of the principle just described would prevent its success in practice, this has been found, through actual experience, not to be the case. Experience 45 has shown that hangers constructed as above described operate with extraordinary ease and entire absence of squeaking or other noise. These hangers never require lubrication, which is a very desirable quality, for 50 it not only costs money to oil hangers, but the oil catches dirt and makes the hangers unsightly and difficult to keep clean.

55 Referring to Figures 1 and 2, it will be noticed that the riders 53 are substantially no longer than the door is wide, and because of the unobstructed run which the wheels have between the riders, it is possible for the axles to roll quite to the ends of the riders. It will be noticed in Figure 1 that the wheel 60 at the left of the figure would impinge on the spreader 55 at about the time the axle of the right hand wheel reached the end of the rider. The wheel at the right hand of the figure would then extend about half its 65 diameter past the edge of the door, but since

that would occur when the door was at the left hand extremity of its run, there would be no objection to this. The point of all this is that the distance between the wheels may be greater, that is, the wheel base of this hanger is longer, in proportion to the space required for the hanger to run in, than that of any hanger of its type heretofore made. This is an important feature in view of the prevailing use of two-part doors. As 70 the panels of a two-part door are usually very narrow, it is important to have the wheel base of the hanger as long as possible, and since the space for the hanger is frequently no longer than the space allotted to 80 the door, hangers of the type here shown have been ill suited to such doors.

While I have shown and described the preferred embodiment of this type of hanger, it 85 is not to be understood that my invention is limited to the structure shown, as various modifications are possible without departure from the spirit of the invention or exceeding the scope of the appended claims.

What I claim is as follows:

1. In a door hanger, a track, a pair of wheels to roll thereon, an axle protruding from each side of each wheel, a pair of links, one on each side of the wheels, the links having recesses in their upper edges in which the axles lie and rotate, said recesses being open at their tops, the links thus connecting the wheels and keeping them a fixed distance apart, but leaving the top of the axles exposed; a pair of riders resting on said axles, one on each side of the wheels and in the same zone as the links, means uniting said riders, and means for connecting the riders to a door.

2. In a door hanger, a track, a pair of wheels to roll thereon, an axle protruding from each side of each wheel, a pair of links, one on each side of the wheels, the links having recesses in their upper edges in which the axles lie and rotate, said recesses nearly 105 surrounding the axles, but having openings at their tops narrower than the diameters of the axles, thus exposing the tops of the axles but enabling the axles to support the links; a pair of riders resting on said exposed parts of the axles, one on each side of the wheels, means uniting said riders, and means for attaching the riders to a door.

3. In a door hanger, a track, a pair of wheels to roll thereon, an axle protruding 110 from each side of said wheels, a pair of links, one on each side of the wheels and having recesses in their upper edges in which the axles lie, the recesses being open at their tops so as to expose the tops of the axles, 115 while connecting and keeping the wheels a fixed distance apart; a pair of rectilinear bars, one on each side of the wheels, their edges resting on the exposed parts of the axles in the same zone the links occupy,

a pair of flat bars bent into a shape resembling an inverted letter **U**, the limbs of said bar being secured to each of the riders, thus uniting the riders, one limb of each bar being extended downward and adapted to connect to a door.

4. In a door hanger, a track, a pair of wheels to roll thereon, an axle protruding from each side of said wheels, a pair of links, 10 one on each side of the wheels and having recesses in their upper edges in which the axles lie, the recesses being open at their tops so as to expose the tops of the axles, while connecting and keeping the wheels a fixed 15 distance apart; a pair of rectilinear bars, one on each side of the wheels, their edges resting on the exposed parts of the axles in the same zone the links occupy, means connecting said riders, a pendent attached to each 20 end of one rider and extending downward, its lower end being bent to form feet extending horizontally under the track; said feet being bifurcated to receive the body of a bolt, the pendants having holes near the 25 bend which join the bifurcations, the holes being large enough to admit the head of a bolt, a pair of bolts to screw into the top of a door, their heads being adapted to pass through said holes and hook on the feet 30 with their bodies in the slots and heads resting on the feet, rectangular washers on said bolts, having flanges to embrace the feet and locate the washers, said washers having slots which permit the bolts to move a limited distance 35 in the feet while preventing the bolts slipping out of the slots, and nuts on the bolts whereby the bolts are rigidly secured to the feet.

5. In a door hanger, a track, a pair of 40 grooved wheels to roll thereon, the treads of the wheels being crowned and the flanges flared slightly outward, said wheels having hubs which are slightly conical, an axle protruding from each side of said wheels, a 45 pair of links, one on each side of the wheels and having recesses in their upper edges in which the axles lie, said recesses nearly surrounding the axles but having openings at their tops narrower than the diameters of 50 the axles, thus exposing the tops of the axles but enabling the axles to support the links, means connecting said links together so they are unable to slip off of the axles, a pair of

riders comprising rectilinear bars standing on edge on the exposed parts of the axles in 55 the same zone the links occupy, means uniting said riders and means for attaching the riders to a door.

6. A door hanger comprising a track, a pair of grooved wheels with fixed axles projecting from each side, a pair of links mounted on said axles to connect the wheels, the apertures to receive the axles being bored so near the upper edges of the links that slots are formed which expose narrow portions 65 of the axles but encircle enough thereof to support the link, and spacers whereby said links are connected together and thus prevent the links slipping off of the axles; a pair of flat rectilinear bars, one of which 70 rests on edge on the axles at each side of the wheels, riding on the axles in the same zone in which the links lie, means connecting the bars, and means for attaching the bars to a door.

7. A door hanger comprising a track, a pair of wheels to roll thereon, axles projecting from each side of said wheels, a rider lying on said axles, and means for connecting said rider to a door; said rider being so constructed that the axles can run to the farthest extremity thereof, thus enabling the axles to run to points in line with the vertical edges of the door, although the space provided for the hanger be no longer than the 85 width of the door plus the distance the door travels.

8. A door hanger comprising a track, a wheel to roll thereon, a pendent carried by said wheel and means for connecting said pendent to a door, the lower end of said pendent being bent to form a foot to extend under the track; said foot being bifurcated to receive the body of a bolt with the head of the bolt resting on the foot, and provided with a hole near the bend to admit the head of the bolt, a bolt to screw into the top of a door, a washer on the bolt, having flanges to embrace the foot of the pendent and prevent the washer becoming displaced, said washer having a slot which permits the bolt to move a limited distance in the slot in the foot but prevents its slipping off of the foot, and a nut for clamping the washer and bolt firmly to the foot.

FRANCIS K. FASSETT.
